UNITED STATES PATENT OFFICE.

FRANK J. BROEST, OF PORTLAND, OREGON, ASSIGNOR OF ONE-HALF TO B. L. SCHNEER,
OF HABANA, CUBA.

COMBINATION WORKSTAND AND TURNTABLE.

Application filed August 14, 1924. Serial No. 732,136.

To all whom it may concern:

Be it known that I, FRANK J. BROEST, a citizen of the United States, and a resident of Portland, county of Multnomah, State of Oregon, have invented a new and useful Combination Workstand and Turntable, of which the following is a specification.

The present invention relates to improvements in a combination workstand and turn table for a motor vehicle and its particular object is to provide a device of the character described that is extremely simple in construction and can be manufactured at such a low cost that it is readily available for any automobile owner in his private garage. A further object is to provide a combination work stand and turn table in which a large number of parts are readily interchangeable and are removably secured to one another so that the device may be easily knocked down and may be conveniently shipped. A further object of the invention is to provide a device of the character described that is symmetrical on opposite sides of a transverse center line and that may be readily turned end for end, either end being adapted to be engaged with a slanting approach allowing the vehicle to be driven on a platform, which latter is elevated above the ground surface so that the chassis of the motor vehicle may be readily worked upon. A further object of the invention is to provide a slanting removable approach and an elevated platform which may be readily engaged with and disengaged from either end thereof, and which when engaged locks the elevated platform against rotation. Further objects and advantages of my device will appear as the specification proceeds.

The preferred forms of the invention are illustrated in the accompanying drawing in which Figure 1 shows a top plan view of one form of my device, Figure 2 a vertical longitudinal section through the same, Figure 3 a plan view illustrating one end of a modified form and Figure 4 a longitudinal section taken along line IV—IV of Figure 3. While I have shown only the preferred forms of the invention it should be understood that various changes or modifications may be made within the scope of the claims hereto attached without departing from the spirit of the invention.

The platform for my device consists of three spaced transverse bars (1) having two

longitudinal runners (2) spaced to conform to the spacing of the vehicle wheels secured thereon by means of screws (3). Spacing members (4) are interposed between the longitudinal runners and rest on the bars (1) to which they are secured by means of screws (6). Guards (7) are secured to the marginal portions of the runners (2).

It will be noted that in this construction a large number of the elements are interchangeable, as for instance the three transverse bars (1), the two runners (2), the three spacing members (4) and the two guards (7). A suitable casting (8) is secured to the bottom face of the central one of the three bars (1) and supports a ring (9) which latter serves as a retaining ring for balls (11) constituting an anti-friction bearing for the standard (12), which latter is secured to the floor represented by the line (13), the floor being preferably an ordinary concrete foundation.

To allow a motor vehicle to be driven on the platform under its own power I provide the slanting approach (14) consisting of a number of boards (16) resting on two slanting supports (17) and side pieces (18) secured to the sides thereof in such a manner as to project beyond the same at the upper end as shown at (19). The approach is of the same width as the platform so that the two projections (19) engage the platform from opposite sides and prevent the same from turning when the approach is in place. The approach may simply rest on the floor or may be made to ride between two guide blocks (21) which prevent lateral shifting of the same.

The platform rides on suitable castors (22) one of which is provided at each corner thereof.

It will be seen from the above description that the platform may be easily knocked down for the purpose of shipping the same and that the interchangeability of the various parts renders the same practically adapted for assembly by a layman. To use the same it is only necessary to erect the standard (12) on the floor of the garage in which it is to be used. While it freely turns when the approach is disconnected from the same the latter holds it against rotation when in place. The approach may be easily disconnected by sliding the same backward a few inches whereupon the platform may

be turned end for end to be again connected with the approach by a slight forward thrust of the same.

I claim:

5. 1. In a combination work stand and turn table for a motor vehicle, a standard, an open horizontal frame pivoted thereon presenting spaced runners for the vehicle wheels, casters pivoted to the four corners 10 of the frame for engagement with the ground surface and a removable slanting approach adapted to be interchangeably engaged with either end of the frame having projections extending from the sides thereof 15 adapted to be brought into sliding engagement with the sides of the frame for locking the same against revolving motion.

2. In a combination work stand and turn table for a motor vehicle, a standard, an open horizontal frame pivoted thereon presenting spaced runners for the vehicle wheels, casters pivoted to the four corners 20 of the frame for engagement with the ground surface and a removable slanting approach 25 adapted to be interchangeably engaged with either end of the frame having projections extending from the sides thereof adapted to be brought into sliding engagement with the sides of the frame for locking the same

against revolving motion, the approach having 30 guide means associated therewith confining the same to longitudinal sliding motion.

3. In a combination work stand and turn table for a motor vehicle, a rotatably mounted elevated frame adapted to support the vehicle wheels thereon and being formed symmetrical on opposite sides of a transverse center line and a removable slanting approach adapted to be interchangeably engaged with either end of the frame having 40 means thereon for preventing revolving motion of the frame when engaged therewith, the approach having guide means associated therewith confining the same to longitudinal 45 sliding motion.

4. In a combination workstand and turn table for a motor vehicle, a frame comprising a transverse bar, two interchangeable end bars evenly spaced therefrom, two interchangeable spaced longitudinal runners removably secured on the three bars, two interchangeable spacing members between the runners secured on the end bars and interchangeable longitudinal guards removably 50 secured to the outer marginal portions of the runner for confining the vehicle wheels. 55

FRANK J. BROBST.
